Des. 189,432
Patented Dec. 13, 1960

189,432

VEHICLE WASHING UNIT

Giuseppe Emanuel, Turin, Italy, assignor to Soc. Acc.
Emanuel di G. e R. Emanuel & C., Turin, Italy

Filed Jan. 30, 1959, Ser. No. 54,398

Term of patent 14 years

(Cl. D49—1)

FIG. 1.

FIG. 2.

FIG. 3.

FIG. 4.

FIG. 5.

Fig. 1 is a front perspective view of a vehicle washing unit, embodying my new design;

Fig. 2 is a top plan view thereof;

Fig. 3 is a rear perspective view thereof;

Fig. 4 is a side elevational view thereof; and

Fig. 5 is an elevational view of the side opposite the side shown in Fig. 4.

I claim:

The ornamental design for a vehicle washing unit, as shown.
